ROOF CONSTRUCTION

Original Filed March 26, 1928 2 Sheets-Sheet 2

UNITED STATES PATENT OFFICE

CLARENCE J. RICHARDS, OF TEMPLE CITY, CALIFORNIA

ROOF CONSTRUCTION

Application filed March 26, 1928, Serial No. 264,749. Renewed May 29, 1930.

This invention relates to roofs.

The general object of my invention is to provide an improvement in roof construction.

5. A further object of my invention is to provide an improved ridge cap for roofs.

Another object of this invention is to provide a ridge cap which may be adjusted to fit any ridge angle.

10. An additional object of this invention is to provide an improved binder for the edge of a roof which is constructed to simulate a tile roof.

15. A further object of my invention is to provide a novel valley construction for roofs.

Other objects of this invention will be apparent from the following description taken in connection with the accompanying drawing wherein:

20. Fig. 1 is a perspective view of a roof constructed according to my invention.

Fig. 2 is an enlarged transverse section through the roof shown in Fig. 1.

25. Fig. 3 is a detailed perspective view of my improved ridge cap.

Fig. 4 is an enlarged perspective view of a single ridge cap end piece.

Fig. 5 is a perspective view of a fragment of the roof edge binder.

30. Fig. 6 is a perspective view on a reduced scale of the roof edge binder.

Fig. 7 is a perspective view of a modified form of roof edge binder showing it used in a valley.

35. Fig. 8 is an enlarged end view of the binder shown in Fig. 7.

Fig. 9 is a perspective view of a valley trough, showing it in connection with a roof.

40. Fig. 10 is a perspective view of the valley trough before it is applied to a roof.

Referring to the drawings by reference characters I have indicated a roof embodying the features of my invention generally

45. at 10. As shown, this roof comprises a plurality of forms 12 having a sinuous upper surface and supported on strips 13 which are in turn supported on rafters 14. The forms 12 are covered with valley shingles 15

50. and crown shingles 16 which are preferably

made of a suitable composition material which may be flexible. The shingles 15 and 16 at the ridge preferably extend over the ridge as shown in Fig. 2.

The ridge of the roof is provided with a 55 ridge cap 18 and the lower eaves edge of the roof is shown as provided with a binder or trim 20. The ends of the ridge cap 18 may be provided with a trimming member 22.

The ridge cap 18 comprises two separate 60 members 24 and 25, (see particularly Fig. 3) each of which have curved upper faces 26 and straight under faces 27. At one side of each of the members 24 and 25 the curved surface 26 joins with the straight under surface 27 and at the opposite side of each of the members 24 and 25 another surface 29 is provided which is disposed at an angle to both the curved surface 26 and the straight surface 27. 65

A rabbet 30 is provided in the straight surface of each of the members 24 and 25 adjacent the juncture of the curved face. The opposite edges of a strip of composition roofing paper 32 are placed in the rabbets 30 of 70 each member 24 and 25 and extend over the curved faces 26 of the members 24 and 25. 75

The composition roofing paper 32 may be secured to the members 24 and 25 as by nailing it thereto as indicated at 33 or in 80 any other desired manner.

By constructing the ridge cap of two separate members 24 and 25 it is adjustable to any pitch of roof.

The ridge cap 18 is placed on top of the 85 ridge shingles 16 and secured to the roof as by nailing it to the crown of the forms 12 as indicated at 35. The trimming member 22 is then nailed to each end of the ridge cap as shown in Fig. 1. 90

The trimming member 22 as shown in Fig. 4 comprises a block of wood 36 formed in any desired shape and covered on its exposed face by a piece of composition roofing paper 37 and the entire peripheral surface of the block 95 is covered with composition roofing paper 38.

The eaves edge binder 20 is formed of metal and includes a flat face 40 (see Fig. 5) a side wall 41 and a top face 42 which is formed sinuous to conform to the shape of the sinuous 100

forms 12. In the valleys of the sinuous top face 42 the metal is slotted to form tongues 43 which are provided with teeth 44.

When the binder 20 is placed on the roof the flat face 40 is positioned on the under side of the forms 12, the ends of the forms abut the side wall 41 and the top face 42 overlays the top surface of the forms 12 as shown in Figs. 2 and 5. The binder 20 may be secured to the forms 12 by nailing it thereto as indicated at 45 in Fig. 2, although the nails 45 may be omitted if desired.

When the binder 20 is in position on the roof the lips 43 are hammered down against the forms 12 so that the teeth 44 are imbedded in the forms as indicated at A in Fig. 5, securing the top of the binder in place. After the binder 20 is placed on the forms the shingles 15 and 16 are laid on the forms and cover the top face of the binder 20.

In Fig. 6 I have shown a section of the binder 20 as it is delivered to a job ready to be positioned on a roof.

In Figs. 7 and 8 I have shown a valley construction wherein binders 50 are positioned on the ends of the forms 12. These binders 50 are formed in the shape of an L and include a base 51, a side wall 52 and a plurality of teeth 53. When delivered the binders 50 are in the form shown in Fig. 8.

A valley construction in which the binders 50 are used includes boards 55 positioned on the rafters 14 and having a strip of composition roofing paper 56 laid over the boards.

The binders 50 are positioned on the forms 12 so that the base 51 is inserted between the bottom of the forms and the roofing paper 56 and the side wall 52 abuts the ends of the forms as shown at B in Fig. 7. After being thus positioned the portion of the side wall which projects above the forms is hammered down on top of the forms so that the teeth 53 are embedded in the forms as indicated at C in Fig. 7, thus firmly securing the binders 50 to the forms 12. To facilitate the forming of the metal to the shape of the forms the side walls are slit with a pair of tin snips as indicated at D in Fig. 7, thus preventing buckling of the metal when it is hammered down. After the binder 20 is secured to the forms the shingles 15 and 16 are laid on the forms and cover the binder 50 as shown in Fig. 7.

In Figs. 9 and 10 I have shown a modified form of valley 60. This valley 60 is formed in the shape of a U and includes a bottom wall 61, side walls 62 and a plurality of teeth 63 on each of the side walls 62.

This valley 60 is delivered to a job shaped as shown in Fig. 10 and is placed between the edges of the opposing forms so that the side walls 62 abut the ends of the forms 12 as shown in Fig. 9. After being correctly positioned on the roof the portions of the side walls 62 which project above the tops of the forms 12 are hammered over on top of the

forms so that the teeth 63 are imbedded in the forms as indicated at E in Fig. 9, thus firmly securing the valley 60 to the forms. Before the projecting edges of the side walls 62 are hammered down over the tops of the forms the side walls are slit with a pair of tin snips as indicated at F in Fig. 9, thus preventing buckling of the metal when it is hammered over the forms.

After the valley is secured to the forms the shingles 15 and 16 are positioned on the forms 12. These shingles cover the top portion of the valley in a manner similar to that shown in connection with the previously described valley in Fig. 7.

From the foregoing description it will be apparent that I have invented an improved roof which is highly efficient, ornamental and may be economically manufactured.

Having thus described my invention, I claim:

1. For use in a roof a metallic valley, said valley being formed U shaped and including a bottom wall and a pair of side walls, said side walls being disposed at approximately right angles to said bottom and each of said side walls including a plurality of teeth arranged at approximately right angles to said side walls and extending outwardly therefrom.

2. In combination with a roof, a metallic valley, said valley being formed U shaped and including a bottom wall and a pair of side walls, said side walls being disposed at approximately right angles to said base and each of said side walls including a plurality of teeth normally arranged at approximately right angles to said side walls and extending outwardly therefrom, said metallic valley being positioned in a roof valley, and the portions of said side walls which project normally upwardly being bent over the edges of said valley with said teeth imbedded in said roof.

3. In combination with a roof including sinuous decking forms covered with shingles, a metallic valley, said valley being formed U shaped and including a bottom wall and a pair of side walls, said side walls being disposed at approximately right angles to said bottom and each of said side walls including a plurality of teeth arranged at approximately right angles to said side walls and extending outwardly therefrom, said metallic valley being positioned between the opposing edges of said forms, the end portions of said side walls being bent over the edges of said forms with said teeth imbedded in said forms.

4. In combination with a roof including rafters, sinuous decking on said rafters and shingles on said decking, a valley formed between opposing edges of said decking, a metallic valley in said first valley, said metallic valley including a base and side walls, a

plurality of teeth projecting from said side walls, said side walls engaging said decking and initially projecting above the top surface of said decking and being bent over said decking to conform to the shape of said decking, said teeth when said side walls are bent over said decking being embedded in said decking, said bent portion of said side walls being adapted to be positioned under roofing shingles.

10 In testimony whereof, I hereunto affix my signature.

CLARENCE J. RICHARDS.
